IRA ULFERS, OF MILWAUKEE, WISCONSIN

COAT COLLAR POSITION RETAINER

Application filed December 19, 1930. Serial No. 503,347.

This invention relates to improvements in coat collar position retainers.

The invention is particularly adapted for use with the coat or outer garment of a man's suit. A man's suit coat, when the wearer is in a sitting or relaxed posture, is very apt to assume a position wherein the coat collar creeps up over the rear portion of the collar of the wearer's inner garment or shirt onto the rear portion of the wearer's neck. The creeping of the coat collar, not only unduly soils the coat collar, but causes the coat to have a rather slovenly and unsightly appearance. Furthermore, the improper position of the coat collar against the wearer's neck is uncomfortable and irritating.

It is, therefore, the primary object of the present invention to provide a collar retaining element adjustably attachable to a coat collar and manipulable to engage a shirt collar whereby the coat collar will always be maintained in a proper non-shiftable position with respect to the inner garment collar.

A further object of the invention is to provide a collar position retainer of the class described which, while securely retaining a predetermined relationship of position between collar portions of inner and outer garments, permits of slight movements of the engaged garment portions so as to prevent straining or tearing the same when the wearer moves.

A further object of the invention is to provide a collar position retainer of the class described equipped with a manipulable spring clip or clasp portion easily accessible and operable to effect engagements and disengagements with the inner garment collar.

A further object of the invention is to provide a coat collar position retainer which is of very simple construction, is strong and durable, is inexpensive to manufacture, is easily secured to a garment in a desired position, and is well adapted for the purposes described.

With the above and other objects in view the invention consists of the improved coat collar position retainer, and its parts and combinations as set forth in the claims, and all equivalents thereof.

In the accompanying drawings in which

the same reference characters indicate the same parts in all of the views:

Fig. 1 is a rear view of the improved coat collar position retainer;

Fig. 2 is a view of the other side of the collar position retainer showing the device as secured to a coat collar with the clasp released and the device in position to be engaged with an inner garment collar;

Fig. 3 is a sectional view through the coat collar showing the retaining device in side elevation in the position shown in Fig. 2 ready for engagement with an inner garment collar;

Fig. 4 is a similar view showing the position of the device with respect to an inner garment collar prior to the clasp portion being engaged or snapped;

Fig. 5 is a similar view showing the final secured position of the device to insure maintenance of the coat collar in proper position with respect to the shirt collar;

Fig. 6 is a front view of one element of an alternative form of position retaining element, said element being adjustably and removably attachable to the inner rear portion of a coat collar;

Fig. 7 is a front view of an element of the same alternative form of the invention, which element is attachable to the rear collar portion of a shirt or inner garment;

Fig. 8 is a view of the element shown in Fig. 6 as secured to a coat collar portion;

Fig. 9 is a sectional view through juxtaposed coat and shirt collar portions showing the elements of the alternative form attached to their respective collar portions and ready for engagement with each other;

Fig. 10 is a similar view showing the releasable engagement of said elements effected to insure non-displaceable retention of the coat collar in proper position with respect to the shirt collar;

Fig. 11 is a sectional view through a coat collar showing in side elevation thereon a slight modification of the element illustrated in Figs. 6 and 8;

Fig. 12 is a front view of the showing in Fig. 11; and

Fig. 13 is a similar view showing an additional slight modification of said element.

Referring now more particularly to the drawings it will appear that the position retaining element comprises a flat strip of a substantial width bent into U-formation with a long outer arm 8 and a short inner arm 9, a recess or pocket 10 being provided between the two arms. The end portion of the inner arm 9 is looped as at 11 and the shank of a safety pin 12 is extended through said looped portion, said retaining element being adapted to pivot or swing on said safety pin shank. An intermediate portion of said short arm 9 is formed with a rectangular slot 13 and also with opposed bearing bosses 14 on opposite sides of said slot 13.

Pivotedly mounted with respect to the intermediate portion of the arm 9 is a yielding, manipulable clasp 15. Said clasp is formed of wire bent into the form of a W, and upper opposed lateral extensions 15' thereof are journaled in the bearing bosses 14. The mid-portion of said clasp is bent angularly outwardly through the slot 13 in the arm 9 to provide an engaging lip 16.

The improved collar retaining element is adapted for securement at a desired position or elevation to the inner rear portion of a coat collar 17. This is accomplished by securing the safety pin 12 to the collar fabric in the usual manner, and the retaining element will then hang from the shank of the safety pin. In order to arrange the element for engagement with a shirt or inner garment collar, the major portion of the clasp 15 is pivotally moved away from the arm 9 to the position shown in Figs. 2 and 3. Said movement of the clasp will turn the lip 16 against the face of the arm 9, leaving the recess or pocket 10 substantially unobstructed. Then, the long arm 8 of the element is slipped between the inner and outer folds 18 and 19 of an inner garment or shirt collar, as shown in Fig. 4. The shank portion of the clasp may then be snapped down against the arm 9, and this will project the lip 16 to engage the outer layer 19 of the collar, clamping it between the arm 8 and said lip. Due to the yieldability of the clasp, especially its mid-portion, the clasp will yield outwardly, depending on the thickness of the fabric engaged thereby, and this is advantageous when a pull or strain is exerted on the coat or shirt, preventing the garments from being injured or torn. Inasmuch as there is merely an edge engagement between the lip and the collar fabric, relative turning movements between the two are permitted, to prevent binding, and freedom of movement of the wearer without strain on the collar.

The clasp of the retaining element, in its closed position, has its shank portion projecting slightly below the lower edge of the element, as best shown in Figs. 1 and 5. This

permits the wearer to easily engage the end of the shank of the clasp for convenient manipulation. As previously described, the device is pinned within the rear collar portion of the coat collar and the correct position therewithin may be easily attained to insure the desired, secured relationship in position between the coat collar and the shirt collar.

In the form of the device illustrated in Figs. 6 to 10 inclusive, the position retaining device takes the form of two complementary elements. The element 22 comprises a metallic member having a female snap fastener socket portion 23. A base strip 24 extends upwardly from the socket portion 23 and is looped, as at 25, to receive the shank of a safety pin 26.

The other complementary element 27 consists of a U-band having a long arm 28 and a shorter arm 29, there being a pocket or recess 30 formed therebetween. Projecting from the outer face of the shorter arm 29 is a male snap fastener stud 31.

In use said form of position retainer is adapted to have the element 22 secured to the rear inner portion of a coat collar 17 at a desired position or elevation by securing the safety pin to the collar fabric in the usual manner, and the element 22 will hang from the shank of the safety pin, as shown in Figs. 8, 9 and 10. The complementary element 27 has its long arm 28 slipped between inner and outer folds 18 and 19 of the rear portion of a shirt collar. The outer fold 19 of the collar is embraced between the arms of said element. As shown in Fig. 9 the complementary snap fastener means of the two elements are then in position for engagement, and as illustrated in Fig. 10, the engagement is effected by snapping the projection 31 into the socket 23, whereby the coat collar is releasably secured to the shirt collar, and its proper position with respect thereto is maintained.

Figs. 11 and 12 illustrate a modification in the construction of the element attached to the coat collar. Said element 22' has bendable prongs 32 extending from its base strip 24, and said prongs are adapted to be extended into the coat collar fabric and bent over for securing the element 22' to the coat collar.

The element 22'', shown in Fig. 13, is similar to the element 22' except that the prongs are eliminated, and in lieu thereof apertures 33 are provided, to permit the element 22'' to be sewed to a garment by thread 34 passed through said apertures and the fabric of the garment.

From the foregoing description it will be seen that the improved coat collar position retainer is of simple and novel construction, and is well adapted for the purposes described.

What I claim as my invention is:

1. In combination, an outer garment, an inner garment, both of said garments having

collar portions, and means carried by one of said garments and releasably engageable with the other for securing the rear collar portions of said garments together to maintain 5 a relationship of position between the two, said means comprising a strip, and a manipulable, yieldable clasp carried thereby.

2. In combination, an outer garment, an inner garment, both of said garments having 10 collar portions, and means carried by one of said garments and releasably engageable with the other for securing the rear collar portions of said garments together to maintain a relationship of position between the 15 two, said means comprising a U-shaped, metallic strip, a securing element carried by an end thereof, and a manipulable, yieldable clasp mounted in an intermediate portion of the strip.

20 In testimony whereof, I affix my signature.
IRA ULFERS.
